OTHER PUBLICATIONS

Pending U.S. patent application Ser. No. 08/191,395, filed Feb. 2, 1994.

Pending Design patent application Ser. No. 019,337, filed Feb. 28, 1994, entitled "On-Site Oil Analyzing Apparatus".

Primary Examiner—Antoine Duval Davis
Attorney, Agent, or Firm—Fish & Richardson

[57] **CLAIM**

The ornamental design for an oil analysis apparatus, as shown and described.

DESCRIPTION

FIG. 1 is a perspective view of an oil analysis apparatus showing my new design, unclaimed structure being shown in dashed lines;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
